ATTORNEYS

UNITED STATES PATENT OFFICE.

WILLIAM W. LEAK, OF MONTGOMERY, ALABAMA.

PLOW.

SPECIFICATION forming part of Letters Patent No. 443,579, dated December 30, 1890.

Application filed April 23, 1890. Serial No. 349,181. (No model.)

To all whom it may concern:

Be it known that I, WILLIAM W. LEAK, of Montgomery, in the county of Montgomery and State of Alabama, have invented a new 5 and useful Improvement in Plows, of which the following is a specification.

My invention is an improvement in that class of plows in which the points or sweep-blades are made of metal sufficiently thin to 10 form an edge, and so avoid the necessity of sharpening and resharpening the said sweep-blades.

The invention consists in certain novel constructions and combinations of parts, as will 15 be hereinafter described, and pointed out in the claims.

In the drawings, Figure 1 is a top plan view, and Fig. 2 is a bottom plan view, of my improved device; and Fig. 3 is a cross-section 20 on about line 3 3 of Fig. 1.

The point or blade A is made of metal sufficiently thin to present edgewise practically a cutting-edge, and is formed of side sections or wings a a, which meet at point a' and form 25 a V shape, as shown. As these points are of light thin metal, it becomes necessary to brace the point, and it is desirable to effect the bracing in such manner as to avoid the addition of any considerable weight to the blade to 30 permit the soil thrown up by the blade to pass readily through and to render the replacing of the wearing parts of such bracing construction easy and inexpensive.

To this end I make the bracing construction in the form of a frame consisting, as 35 shown, of cross-bar B and the connecting-bar C, which form a T, as shown. The bar B extends between the wings a, and is secured rigidly to both such wings at a point near 40 their free ends, usually by riveting, as shown.

The bar C connects at its free end with the under side of the blade A at the point thereof or juncture of the wings a, and is preferably secured by riveting, as shown. At its opposite end the bar C laps against the bar B at the 45 middle of the latter, and both bars B and C

have coincident holes for the heel-screw of the plow, so that the said bars B and C are secured by the same screw which fastens the plow to its standard or support. The bars B and C 50 form a positive brace and enable the use of much thinner steel than could be otherwise used. The bar B is subject to no considerable wear, and is practically indestructible, while the bar C, if worn at its point, may be 55 removed and resharpened, or may be replaced at a slight cost. The brace-frame being open also permits the free passage of the soil thrown up by the sweep-blade.

By using bars B and C, as shown, I dispense 60 with all useless material, and so lighten and cheapen the construction.

The point or blade A may be secured to the plow stock or standard D by means of the screw or bolt d, passed through the bars B 65 and C at their juncture, and then through the part D and secured by a nut or in other suitable manner.

Having thus described my invention, what I claim as new is—

1. The combination, substantially as described, of the V-shaped sweep having its side wings diverging from its point, and the T-shaped open brace-frame having its arms secured to the sweep at the point thereof and 75 at or near the free ends of its side wings, all substantially as described, and for the purposes set forth.

2. The improvement in plows, substantially as herein described, consisting of the V- 80 shaped sweep having the side wings united at one end, the cross-bar B, extended between and secured to such wings near their free ends, and the bar C, secured at one end to the sweep at the juncture of its wings and connected at its opposite end with the cross-bar B at about the middle of the latter, substantially as set forth.

WILLIAM W. LEAK.
